Attorney

UNITED STATES PATENT OFFICE

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK

RAIL JOINT

Application filed September 10, 1930. Serial No. 481,021.

This invention relates to rail joints of the type in which the joint bar has head clearance at its ends from the rails, head contact medially with the rails at the meeting ends 5 of the latter, and base contact at its ends with the rail flanges, whereby the rail ends may be elevated by drawing the joint bar inward relative to the rails and whereby energy may be stored in the joint bars by tightening the joint 10 bolts to maintain the rail ends high and the joint tight, and the general object of the invention is to provide a rail joint of this type which is simple in construction and of economical production and maintenance cost.

Heretofore, in rail joints of the type mentioned, it has been the practice to form the joint bars of irregular height and section for contact with the rails in the manner stated, and this has required that the joint bars 20 either be forged or cast at relatively high expense. Accordingly, one of the special objects of the present invention is to provide a joint bar for contact with the rails in the manner stated, which bar is, or may be, of uniform height and section throughout its 25 length, whereby the same may be produced economically and with facility by simple rolling and bending operations.

With the foregoing and other objects in view, which will become more fully apparent as the nature of the invention is better understood, the same consists in the novel features of construction, combination and arrangement of parts, as will be hereinafter 35 more fully described, illustrated in the accompanying drawings and defined in the appended claims.

In the drawings, wherein like characters of reference denote corresponding parts in the 40 different related views:

Figure 1 is a side elevation of a rail joint constructed in accordance with one practical embodiment of the invention.

Figure 2 is a horizontal section through 45 the rail joint illustrated in Fig. 1, showing the joint bars in top plan view.

Figure 3 is a transverse section on the line 3-3 of Fig. 1.

Figure 4 is a transverse section on the line 50 4-4 of Fig. 1.

In the illustrations of each embodiment of the invention the rails are designated as R, R', respectively, and the joint bar as B.

With respect to the joint bar B illustrated in Figs. 1 to 4, it will be noted that the same 55 is of uniform height and of uniform cross-sectional area throughout its length. Manifestly, therefore, said bar is capable of being produced as a new bar by a simple, economical rolling and pressing operation. 60

Preferably, the bar B is of the so-called Headfree type. That is to say, its head 10 preferably is formed for loading engagement with the head fillets 11 of the rails, and for clearance from the undersides of the rail 65 heads. However, viewing the invention in its broader aspects, this is not essential, as the bar may be formed for head fishing contact with the undersides of the rail heads. Moreover, according to the broader aspects 70 of the invention, the particular cross sectional design of the bar is immaterial.

As will be noted by particular reference to Figs. 1 and 2 of the drawings, the end portions b, b of the bar B are offset or deflected downward and outward so that when the bar is operatively engaged with the rails, only the medial portion of the head 10 takes loading engagement with the head fillets 11 of the rails and a clearance space 12 exists 80 at the ends of the bar between the head thereof and the head fillets of the rails, while the base 13 of the bar usually takes fishing contact throughout its length with the upper faces of the base flanges 14 of the rails. Consequently, by properly manipulating the joint 85 bolts to draw the bar inward with respect to the rails, the ends of the latter obviously may be elevated and a bending moment may be imposed on the ends of the bar to store 90 energy therein to maintain the joint tight.

Either in the same operation with the production of the present bar, or subsequently to such operation, the ends of the bar are offset or deflected downwardly and outwardly 95 to provide for the clearance of the head of the bar at its ends from the head fillets of the rails, (see Fig. 4) and preferably for continuous fishing contact of the base of the bar with the upper surfaces of the rail 100

flanges, it being understood in this latter connection, of course, that the amount of downward and outward deflection of the ends of the bar is determined by the angularity of the upper surfaces of the rail flanges so that the base of the bar may have continuous contact with said surfaces as stated. Thus, the present bar, possesses all of the characteristics and all of the advantages of the prior art bar heretofore mentioned which is capable only of being forged or cast, and in addition possesses the advantages that it may be produced as a new bar by a simple rolling and bulldozing process.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. In a rail joint, the rails, and a joint bar of uniform height throughout its length having head clearance at its ends from the rails, medial head contact with the rails, and base contact with the rail flanges.

2. In a rail joint, the rails, and a joint bar of uniform height and cross-sectional area throughout its length having head clearance at its ends from the rails, medial head contact with the rails, and base contact with the rail flanges.

3. In a rail joint, the rails, and a joint bar of uniform height throughout its length deflected downwardly and outwardly at its ends to provide head clearance at its ends from the rails and base contact at its ends with the rail flanges, the medial portion of the head of said bar having loading engagement with the rails.

4. In a rail joint, the rails, and a joint bar of uniform height throughout its length deflected downwardly and outwardly at its ends to provide head clearance at its ends from the rails and base contact at its ends with the rail flanges, the medial portion of the head of said bar having loading engagement with the head fillets of the rails and head clearance from the underside of the rail heads.

5. In a rail joint, the rails, and a joint bar of uniform height and cross-sectional area throughout its length deflected downwardly and outwardly at its ends to provide head clearance at its ends from the rails and medial head contact with the rails, the base of said bar having contact throughout its length with the base flanges of the rails.

6. In a rail joint, the rails, and a joint bar of uniform height throughout its length having head clearance at its ends from the rails, medial head contact with the rails, and

base contact with the rail flanges, said bar being inclusive of a foot flange having a medial portion extending farther outward than portions to either side of said medial portion.

7. In a rail joint, the rails, and a joint bar of uniform height throughout its length having head clearance at its ends from the rails, medial head contact with the rails, and base contact with the rail flanges, said bar being inclusive of a foot flange having medial and end portions extending farther outward than the portions disposed between said medial and said end portions, respectively.

8. A rail joint including the rails, and a joint bar provided with a medial head portion having a loading engagement solely with the head fillets of the rails, and with end portions having clearance at the head from the rails and at the base having a bearing engagement with the upper sides of the rail flanges.

In testimony whereof I hereunto affix my signature.

VICTOR C. ARMSTRONG.
